UNITED STATES PATENT OFFICE.

WARREN S. JOHNSON, OF MILWAUKEE, WISCONSIN.

HEATING SYSTEM.

SPECIFICATION forming part of Letters Patent No. 773,078, dated October 25, 1904.

Application filed April 1, 1898. Serial No. 585,789. (No model.)

To all whom it may concern:

Be it known that I, WARREN S. JOHNSON, a citizen of the United States, residing at Milwaukee, in the county of Milwaukee and State 5 of Wisconsin, have invented certain new and useful Improvements in Heating Systems, of which the following is a specification.

My invention relates to that class of heating systems in which an exhausting apparatus 10 is placed in communication with the radiator or radiators to remove the air or produce a partial vacuum therein, and thereby to facilitate the distribution of the heating agent or medium. Such systems being already well 15 known to the public need not be particularly described herein.

The invention consists in providing the radiators each with a supply or controlling valve and with a fluid-pressure motor for actuating said valve, connecting the fluid-pressure motor with the exhaust pipe or system, providing said exhaust-pipe with a vent at a point between the exhauster and the fluid-pressure motor, and applying to said vent a 20 thermostatic valve whereby the one exhaust system is caused to exhaust the air from the radiators and to control and actuate the supply or controlling valves.

The fluid-motor valve and the thermostatic 25 vent-controller employed are not specifically claimed, being those of the well-known Easton type; but the combination whereby one exhaust system is made to serve both purposes and to insure the proper relative working of 30 the different parts of the system is new and affords an exceedingly simple, cheap, and efficient means of temperature regulation and control.

The accompanying drawing represents the 35 improved apparatus in elevation with portions in section, the whole being of a dia-grammatic nature.

A indicates a radiator; B, its supply-pipe provided with a main controlling-valve C; D, 40 the return or discharge pipe; E, an air valve or vent for the radiator; F, an exhaust-pipe communicating by a branch a with air valve or vent E, and G an exhausting apparatus, herein represented as a positively-acting 45 pump.

As shown, main valve C is carried by a stem b, connected with the flexible diaphragm c of a fluid-pressure motor H, said stem b being encircled by a spring d, which tends always to open valve C.

When pipe F is sealed against the atmosphere, the suction of pump or exhauster G produces a partial vacuum in the fluid-chamber of motor H, and as a consequence the pressure of the atmosphere upon its diaphragm causes 55 the latter to collapse into the chamber of the motor and in so doing to lift and close valve C, thereby shutting off the supply of heating medium or agent. If, however, the pipe F be freely vented or opened to the outer atmosphere, the suction or exhaust from 60 motor H will be insufficient to close valve C, and consequently the radiator will be supplied with the heating agent or medium, this being the relation of parts represented in the 65 drawing.

Pipe F is represented as furnished with a vent-pipe e, to the vent-orifice of which is applied a thermostatic valve I. When the main valve C is arranged to open against and to close with the suction, as here represented, valve I will be arranged to close upon a rise of temperature; but if the main valve be arranged to open with or by the suction and to close when suction ceases valve I will of course 70 be arranged to close upon a fall of temperature. Being set to close as the temperature rises to a predetermined limit, under the embodiment of the invention here represented valve I will seal the pipe F against communication with the atmosphere whenever the apartment is sufficiently warmed, and the consequent suction upon the diaphragm c of motor H will close valve C and shut off the heating medium. When the temperature falls 75 sufficiently to cause the thermostatic valve to unseal vent-pipe e, the motor H being relieved of suction its valve C will open and supply more of the heating medium to the radiator. In this way the one exhaust system 80 is made to serve both to exhaust the radiator and to control or actuate the main heat-regulating valve.

An outwardly-opening check-valve J is applied to the radiator to permit escape of wa-

ter of condensation or passage of steam, but to prevent ingress of air, which would interfere with the proper exhausting action.

Branch pipe *a* may be made of smaller capacity than pipe *F* or vent *e*, so that it shall not interfere with the proper action and control of motor *H*, and a restriction of some kind will be made between the exhausting apparatus and the vent or the branch pipe containing the vent, thus making the normal area of the exhaust-pipe smaller than the vent. The first of these provisions is not essential and may be disregarded if the exhausting apparatus have a reasonable margin or surplus of capacity. The second provision is, however, important, as otherwise the exhausting apparatus might maintain a constant suction or exhausting action in the fluid-pressure motor, and thereby cause the main valve to remain always closed. While it is possible to so nicely adjust the capacity of the exhausting apparatus to the size of the vent and the capacity of the exhaust-pipe as to operate without the restriction, it is not considered wise to adopt such construction. At the same time I do not mean to restrict myself to the employment of a restriction and thereby to exclude apparatus omitting the same.

Having thus described my invention, what I claim is—

1. In combination with a radiator; a supply-pipe for delivering a heating medium thereto; a valve for regulating the delivery of heating medium; a fluid-pressure motor for actuating said valve; a pipe communicating with the fluid-pressure motor and with the radiator; an exhausting device communicating with said pipe; a vent for said pipe located

between the motor and the exhauster; and a thermostatic valve applied to said vent; all substantially as and for the purpose set forth.

2. In a heating system, the combination of a radiator; a valve controlling the supply of heating medium thereto; a motor for actuating said valve; a vent controlling the action of the motor; a thermostatic valve controlling said vent; and an exhauster common to the radiator and the motor, the pipe connecting the exhauster with the motor and radiator being restricted at a point between the radiator connection and the vent.

3. In combination with radiator *A*; supply-pipe *B*; valve *C*; motor *H*; exhaust-pipe *F*; branch pipe *a* connecting the exhaust-pipe *F* with the radiator; vent-pipe *e*; thermostatic valve *I* applied to vent-pipe *e*; and exhauster *G*; all arranged to operate substantially in the manner set forth.

4. In combination with a radiator, a supply-pipe for delivering the heating medium thereto, a valve for regulating the delivery of the heating medium, a fluid-pressure motor for actuating said valve, a pipe communicating with the fluid-pressure motor and with the radiator, an exhausting device communicating with said pipe, a vent for said pipe located between the motor and the exhauster, and an automatic valve applied to said vent, substantially as and for the purpose set forth.

In witness whereof I hereunto set my hand in the presence of two witnesses:

WARREN S. JOHNSON.
